UNITED STATES PATENT OFFICE.

HARRY SEARLE, OF WORCESTER, MASSACHUSETTS, ASSIGNOR TO COES WRENCH COMPANY, OF WORCESTER, MASSACHUSETTS, A CORPORATION OF MASSACHUSETTS.

CONSTRUCTION OF WRENCHES.

SPECIFICATION forming part of Letters Patent No. 705,875, dated July 29, 1902.

Application filed April 18, 1902. Serial No. 103,557. (No model.)

To all whom it may concern:

Be it known that I, HARRY SEARLE, a citizen of the United States, residing at Worcester, in the county of Worcester and State 5 of Massachusetts, have invented a new and useful Improvement in the Construction of Wrenches, of which the following, together with the accompanying drawings, is a specification sufficiently full, clear, and exact to 10 enable persons skilled in the art to which this invention appertains to make and use the same.

This invention relates to means for securing the jaw-adjusting screw in a screw-wrench 15 against endwise displacement in relation to the wrench-bar, the object being to provide a guard-pin or rigid stud permanently fixed in the front of the bar and projecting outward therefrom for engagement with the rosette or thumb-boss of the screw, as herein-after explained and as illustrated in the accompanying drawings, wherein—

Figure 1 represents a side view of a "Coes" wrench having my improvement embodied 25 therein. Fig. 2 is a front view of a portion of the wrench-bar, showing the guard-pin fixed therein. Fig. 3 is a transverse section at line X X on Fig. 1. Fig. 4 is a vertical section at the lower end of the adjusting-screw. Fig. 5 is a section at line Y Y on Fig. 1, showing the bottom end of the sliding jaw. Fig. 6 is a transverse section similar to Fig. 3, but showing the guard-pin as made with a T-head; and Fig. 7 is a front view of 35 a portion of the wrench-bar, showing the T-headed pin.

In the drawings, A denotes the wrench-bar, having the fixed jaw a on the upper end thereof and the handle-supporting shank A' at its 40 lower end.

B indicates the movable jaw, that slides on the wrench-bar in usual manner; C, the jaw-adjusting screw, provided with the rosette-head C' and end journal c², and D the top 45 end of the handle-frame or collar portion, which is fitted upon the bar-shank and against the positioning-shoulders d and carries the projecting bearing-step D³, within which the journal of the screw is supported at a position that will permit the rosette-head C' to

stand clear from the front plane of the wrench-bar, all in well-known arrangement.

As a feature of my present invention I provide on the front of the wrench-bar at a position adjacent to the rosette-head C' a projecting pin or guard-stud I, which is permanently fixed or solidly incorporated in the body of the wrench-bar and has an end portion thereof that projects outward over the edge of the rosette C' or engages therewith in such manner that the screw C, while it is free to rotate without interference, cannot be moved endwise sufficiently to release the journal c² from the bearing-step D³, owing to contact and arrest by the rigid pin I. For supporting the pin I a hole is formed in the front of the wrench-bar at the position desired, and the pin is inserted therein after the slideable jaw B has been assembled on the wrench-bar, but before the screw is assembled therein. The pin I is driven into the hole and is then made fast and solidly incorporated with the bar by staking up the metal of the wrench-bar around the pin, as indicated at m, by means of a suitable staking-tool, thus fixing 75 the pin permanently in position with its outer end projecting, as shown. The screw C is then screwed into the jaw B and the handle D assembled upon the bar-shank and against the shoulder d, said handle-frame being secured upon the bar-shank in well-known or suitable manner. The rosette then occupies a position between the end of the handle-frame and the pin I, and is thereby confined against endwise movement, while its free rotative 85 movement is permitted.

The neck of the pin can be made of slightly smaller diameter than the inner end, so that the staking up of the metal of the bar will give a firm hold upon the pin.

The lower end of the slideable jaw B is preferably provided with a recess or cavity b of suitable depth, (see Fig. 5,) into which the projecting portion of the pin I can enter when the jaw B is completely opened, thus allowing the jaw-body, which would otherwise strike the top of the pin I, to pass down to the rosette and the jaw to be opened to its fullest extent.

In some instances the guard-pin may be 100

- made with a broad flat end or T-head, substantially as illustrated at I' in Figs. 6 and 7, the projecting portion being of greater dimension than the inserted portion, said T-
 5 head affording a somewhat-greater wearing-surface against the rosette. Said pin can also, if desired, be integrated with the wrench-bar by brazing, sweating, or soldering it permanently in position.
- 10 What I claim herein as of my invention, and desire to secure by Letters Patent, is—
 1. In a wrench of the class described, the combination with the wrench-bar, the handle-frame or collar portion carrying the bearing-step, the slideable jaw, and the jaw-adjusting screw journaled in said step, and having the rosette thereon standing clear of the front plane of the wrench-bar; of a guard pin or stud inserted and solidly fixed at one end in
 15 the metal of the front edge of said wrench-bar, with its projecting outer end in overlying engagement with the rosette, and confining said adjusting-screw against endwise displacement.
- 20 2. In a wrench of the character described, in combination with the wrench-bar; the screw-supporting step and the jaw-adjusting screw, of guard pin or stud inserted in an opening in the front of the wrench-bar above
 25 the top edge of the rosette, and solidly in-

corporated therein by staking in the metal of the bar around the neck of the pin, the head of the pin projecting outward above the rosette, substantially as set forth.

3. In combination, with the wrench-bar, 35 the sliding jaw, the handle-frame and the adjusting-screw having the rosette thereon; a guard-pin fixedly inserted in the front of said wrench-bar, and having the head or projecting portion of greater width than the inserted 40 portion, for the purpose set forth.

4. In a wrench of the character described, in combination, with the wrench-bar, the handle-collar, and jaw-adjusting screw having the rosette thereon; a protuberant pin or 45 retaining member supported in the wrench-bar and projecting over the edge of the rosette for endwise confinement of the screw, and the slideable jaw arranged on said wrench-bar and screw, said jaw being provided with a 50 recess or cavity at its lower end into which said retaining member is received when said jaw is at fully-opened position.

Witness my hand this 15th day of April, 1902.

HARRY SEARLE.
